US00D581151S

(12) United States Design Patent
Aipa

(10) Patent No.: US D581,151 S
(45) Date of Patent:  Nov. 25, 2008

(54) PORTABLE ELECTRONIC DEVICE CASE

(75) Inventor: Moses Aipa, Pasadena, CA (US)

(73) Assignee: Incase Designs Corporation, Irwindale, CA (US)

() Term: 14 Years

(21) Appl. No.: 29/303,870

(22) Filed: Feb. 19, 2008

(51) LOC (8) Cl. 03-01

(52) U.S. Cl. D3/201; D3/218

(58) Field of Classification Search D3/218, D3/201, 215, 226, 269, 272-273; 206/305, 206/320; 455/90, 92, 42; 379/455; 224/901, 224/904, 240-241, 245, 682-683; D14/469, D14/156, 138

(57) CLAIM

The ornamental design for a portable electronic device case, as shown and described.

DESCRIPTION

FIG. 1 shows a perspective view of a first embodiment for a design for a portable electronic device case.

FIG. 2 shows a front view of the first embodiment.

FIG. 3 shows a back view of the first embodiment.

FIG. 4 shows a left side view of the first embodiment.

FIG. 5 shows a right side view of the first embodiment.

FIG. 6 shows a top side view of the first embodiment.

FIG. 7 shows a bottom side view of the first embodiment.

FIG. 8 shows a perspective view of a second embodiment for a design for a portable electronic device case.

FIG. 9 shows a front view of the second embodiment.

FIG. 10 shows a back view of the second embodiment.

FIG. 11 shows a left side view of the second embodiment.

FIG. 12 shows a right side view of the second embodiment.

FIG. 13 shows a top side view of the second embodiment.

FIG. 14 shows a bottom side view of the second embodiment.

FIG. 15 shows a perspective view of a third embodiment for a design for a portable electronic device case.

FIG. 16 shows a front view of the third embodiment.

FIG. 17 shows a back view of the third embodiment.

FIG. 18 shows a left side view of the third embodiment.

FIG. 19 shows a right side view of the third embodiment.

FIG. 20 shows a top side view of the third embodiment.

FIG. 21 shows a bottom side view of the third embodiment.

FIG. 22 shows a perspective view of a fourth embodiment for a design for a portable electronic device case.

FIG. 23 shows a front view of the fourth embodiment.

FIG. 24 shows a back view of the fourth embodiment.

FIG. 25 shows a left side view of the fourth embodiment.

FIG. 26 shows a right side view of the fourth embodiment.

FIG. 27 shows a top side view of the fourth embodiment; and, FIG. 28 shows a bottom side view of the fourth embodiment.

The broken-line features in the figures are for illustrative purposes only and form no part of the claimed design.
